CIRCULAR KNITTING MACHINE

Albert E. Page, Brooklyn, and Harry Swinglehurst, Jr., Wantagh, N. Y., assignors to Scott & Williams, Incorporated, Laconia, N. H., a corporation of Massachusetts

Application September 14, 1938, Serial No. 229,970

13 Claims. (Cl. 66—49)

This invention relates to stitch slackening means for circular knitting machines and more particularly to means for slackening stitches in spliced fabric areas of varying width, such as a cradle sole or tapered high splice in a stocking.

It has been known heretofore to slacken the stitches in the spliced areas of stockings in order to permit the introduction of sufficiently heavy thread or threads in the stitches. One of the objects of the present invention is to make this slackening possible where the width of the reinforcement varies from course to course and to make the slackening coincide accurately with the limit of the splicing. It is characteristic of the present invention that the means for changing the stitch length as the machine goes from the unslackened stitches to the slackened stitches is controlled by the knitting instrumentalities which determine the extent of the spliced area.

The invention will be shown and described in a Scott & Williams revolving needle cylinder seamless hosiery machine containing rocking jacks and jack selecting means of the type shown in the patent to Ivan W. Grothey No. 1,678,385, dated July 24, 1928. The invention is embodied in a machine in which a splicing finger and knitting instrumentalities are brought into and out of yarn engaging positions by raising needles selectively. This gives differentiation in the position of the butts of the jacks, and this differentiation is availed of to cause the slackening operation.

In the drawings,

Fig. 1 is an elevation from the left side of a Scott & Williams machine containing the invention, showing mechanism for slackening by means of the sinkers;

Fig. 2 is a view in side elevation of the foot of a seamless stocking showing a cradle sole and irregular high splice with the slackened areas shaded;

Fig. 3 is a plan view of the lower bedplate of the machine of Fig. 1, taken on the line 3—3 of Fig. 1, showing the special cams for operating on the pattern jacks in connection with the slackening of the stitches;

Fig. 4 is a detail view in plan of the special drawdown cam lever connection to its thrust rod;

Fig. 5 is a plan view of part of the sinker cap showing the sinker slackening cam of Fig. 1 and its controls;

Fig. 6 is a detail view in elevation from the right side of the machine showing the mounting

of the swinging bracket which carries the special drawdown cam shown in Fig. 3;

Fig. 7 is a development of the cam ring viewed from the inside of the machine, showing the path of the pattern jacks whose butt differentiation is used to control the stitch slackening, the arrow showing the direction of movement of the needles and jacks; while

Fig. 8 is a perspective skeleton view from the right rear of the machine showing a modified form of mechanism for slackening the stitches, in which the slackening is caused by vertical movement of the stitch cam, the arrows indicating the direction of movement of the parts when going to stitch slackening position.

In the modern seamless stocking with its fine thread and with stitches as small as desired in the unreinforced areas, it is frequently impossible to crowd any splicing threads at all into the stitches for the spliced areas without slackening the stitches. If the stitches are slackened it is possible to get as much as five or six threads in the spliced stitches, and this is frequently desirable. It has been known heretofore to slacken the stitches in local, i. e., sectional spliced areas such as high splices or soles of seamless hosiery, but no satisfactory method has been known heretofore of making such slackening conform accurately with the outlines of a spliced area whose width varies. Thus, for instance, in making a cradle sole in a stocking it has been exceedingly difficult to devise any mechanism which will cause all the splicing stitches to be slackened, and on the other hand will not slacken any stitches which are not reinforced. The best method of making reinforced areas of varying width is to use needle selection for determining the needles whose stitches are to be reinforced. According to the present invention, vertical selection of the needles or their pattern jacks is availed of to give a butt differentiation which is transmitted to one or another of the stitch-making elements to cause slackening of those specific stitches and those only. In the embodiment of the invention shown in Figs. 1 to 7, the slackening is caused by extra movement of the sinkers, but in the modification of Fig. 8 the slackening is obtained by vertical movement of the knitting cam.

We will first describe the embodiment of Figs. 1 to 7, which is the preferred form. There are the usual main pattern drum 120, needle cylinder 260, lower bedplate B and upper bedplate C. There are pattern jacks 732 controlled from the space between the lower bedplate B and the

upper bedplate C, while the manipulation of the needles themselves takes place above the upper bedplate C. On the upper end of the needle cylinder is the usual outside sinker cap 300 in which are located the cams for moving the sinkers S in between the needles N. As shown in Fig. 5, there is mounted in the sinker cap 300 a special push-in cam 309 which determines the extent of the inward thrust of the sinkers. This may be termed the "sinker selecting cam." This cam 309 is normally held outward in its outward operating position by a tension spring 310 extending from the end of the cam to a nearby post on the upper bedplate C (see Fig. 5). In this position, a regular cam 308 draws yarn for stitches which are to be normal in length. When it is desired to draw stitches of abnormal length in order to slacken the stitches because they are reinforced, the cam 309 is moved inward until it contacts an adjustable guide 311 mounted on the cam ring.

We will now describe the mechanism controlled from the jacks which selects the needles to take the splicing yarn. This mechanism has for its primary control the main pattern drum 120. This primary control acts through one of the usual thrust rods 460 passing through the lower comb 451 and held down in contact with the surface of the main pattern drum or the cam in its path by means of a tension spring 452 running between a notch in the thrust rod and the lower comb. Mounted on the thrust bar 460 just below the upper bedplate C is an adjustable cam plate 456 which pushes the upper end of the thrust bar 460 radially outward when the bar is raised by a cam on the main pattern drum. This tipping of the thrust bar radially outward or away from the bedplate serves to insure that the sinker slackening cam 309 goes to its retracted position, shown in Fig. 5. The connections between the upper end of the thrust bar 460 and the sinker slackening cam 309 which make this possible are as follows. To push the sinker slackening cam inwards there is a sliding finger 453 carried by a plate 454 which is slidably mounted on the usual latch ring bracket 401. There is a tension spring 455 extending between the latch ring bracket 401 and the upper end of the thrust bar 460 which tends to push the finger 453 radially inward against the sinker slackening cam 309. Since the finger 453 is pivoted to the upper end of the thrust bar 460, it follows that when the thrust bar 460 is pulled away from the upper bedplate C, the finger is retracted out of contact with the sinker slackening cam 309 and that cam will be freed to be retracted by its own tension spring 310. The cams on the main pattern drum 120 lying in the path of this thrust bar 460 are so located as to hold the thrust bar in its uppermost position, where the sinker slackening cam is in its normal or retracted position, except when spliced areas are to be made. When spliced areas are to be made, the thrust bar drops down into the surface of the main pattern drum, and the upper end of the bar is pulled towards the upper bedplate C by the tension spring 455. This also serves to release the thrust bar and the sinker slackening cam to be controlled by the secondary means which acts on each revolution of the machine to cause sectional or local splicing in accordance with the pattern jack selection.

The elements which transmit the jack butt differentiation to the thrust bar 460 comprise a bent arm 185 pivotally mounted on the side of the thrust bar, with its lower end extending

around to the back of the thrust bar, where its exact angle of contact is determined by a set screw 186. The upper end of this bent arm 185 is attached to a connecting link 187 which in turn is connected to an operating lever 188 adapted to read the butts of the pattern jacks 732. This operating lever 188 is pivotally connected to a link 187 and is pivotally mounted at the opposite end on a post 189 projecting upwardly from an adjustable bracket 190 on the lower bedplate B of the machine. This bracket 190 is adjustable circumferentially of the machine and thus provides an adjustment for the operating lever 188 (see Fig. 3). These parts are so arranged that when the reading point 191 of the operating lever 188 rides up on a series of butts on the pattern jacks, the thrust bar 460 will be pushed away from the upper bedplate against the tension of spring 455, thus permitting the tension spring 310 to retract the sinker slackening cam 309 and prevent the drawing of slackened stitches. Whenever the reading point 191 of the operating lever 188 finds no pattern jack butt opposite it and it drops in towards the surface of the needle cylinder, the linkage 185 to 188 is relaxed and the tension spring 455 pulls the thrust rod in toward the upper bedplate C, pushing the sinker slackening cam 309 inwardly to the point where it will draw slack stitches.

We will now describe the mechanism which causes the pattern jack selection or butt differentiation. The operating lever 188 is at the rear of the machine, as shown in the plan view of Fig. 3, and it is necessary to prepare the butt differentiation before the jacks get around to the operating lever. (The pattern jacks and needles revolve in a counterclockwise direction, as viewed from above.) As viewed in Fig. 7, the jacks and the needles move from right to left, and the reading point 191 of the operating lever 188 is shown about the center of the drawing. In the particular embodiment shown in Figs. 1 to 7, the cams and butts are so arranged that butts on all pattern jacks whose needles are not going to take the splicing yarn will be placed at a slightly lower level than usual and at this level they will meet the reading point 191 of the operating lever 188. This preparation takes place at a point almost 180° in advance of the position of the point 191 of the operating lever. Near this point there is a pattern jack raising cam 741 adapted to raise all pattern jacks whose lower ends were not pressed radially inward by the appropriate selecting means (not shown) shortly prior to arriving at this raising cam 741. Jacks thus raised cause their needles to take the splicing yarn. The machine is set so that the lower ends of the jacks whose needles are not taking splicing yarn are pressed radially inward, and these jacks will not be raised on the cam 741, which in turn causes the raising of the needles to a level where they can take the splicing yarn. Near the middle of each pattern jack is a lowering butt 737, 737', so located that when a jack does not ride up the raising cam 741 it will be acted on by a special drawdown cam 15. The butts on the non-splicing needle jacks are marked 737', and the butts on the jacks for the splicing needles, 737. The drawdown cam 15 is adapted to lower jacks to a point say $\frac{3}{32}$ of an inch lower than the normal level, and at this level the butts 737' on the jacks are at the same level as the operating lever 188. The levelling cam 752 holds them up to this level. After passing cam 15 the levelling cam 753 brings the butts 737' to normal level. This drawdown cam 15 is located

at a point shortly following the maximum height of the cam 741, and it lowers all jacks which did not rise on cam 741, but does not touch those which did go up that cam (see Fig. 6). The jacks which rose up the cam 741 come down to their normal level beyond the cam 15 and therefore the operating lever 188 is not engaged by the butts 737 on the jacks which took the splicing yarn. From an examination of Fig. 7 it will be seen that 10 the raising of certain pattern jacks 732 on the cam 741 in order to cause their associated needles to take the splicing yarn occurs in the same course of fabric as the slackening of sinkers caused by the operating lever 188. (The stitch cam 360 is 15 almost directly above the reading point 191.)

The drawdown cam 15 itself is mounted on a swinging bracket 192 pivoted on a bracket carrying the cam 741. There is a tension spring 193 between the upper portion of the bracket 192 and 20 the bracket on the bedplate tending to keep the drawdown cam in retracted position. There is a long horizontal lever 194 pivotally mounted on the bedplate near the rear (see Fig. 3), whose rear end hooks around a cam 195 on the upper 25 end of a thrust bar 461 (see Fig. 4). When the thrust bar 461 is lowered, the long lever 195 swings and pushes the drawdown cam 15 into its operative position where it will lower those jacks whose needles are not taking splicing 30 yarn. This causes the necessary butt differentiation above referred to.

The construction of the embodiment of Figs. 1 to 7 having been described, its operation will now be set forth. Assuming that the machine has reached the point where it is desired to make a stepped high splice or a cradle sole, the pattern chain will cause the main pattern drum 120 to rack ahead in the usual manner. This causes the thrust bar 460 to drop down onto the surface 40 of the main pattern drum, which releases it from camming action of the adjustable cam 456, releasing the thrust bar and sinker slackening cam 309 to the secondary control means associated with the butts 737. Simultaneously 45 the thrust bar 461 drops down sufficiently far to cause the long lever 194 to push the special drawdown cam 15 into its operative position. As soon as the jack selecting mechanism goes into action, some of the pattern jacks start riding up the cam 741 to take splicing yarn. In 50 this way a space will be created in the row of butts at the level of the reading point 191, the butts 737 for the spliced stitches being above the lever 188. As soon as this space in the butts 55 reaches the reading point 191, the operating lever 188 will move in towards the surface of the pattern cylinder, pulling the thrust bar 460 radially inward and causing the finger 453 to push the sinker slackening cam 309 inward to the point 60 where it will draw slack stitches. As soon as the section or group of jacks corresponding to needles which take the splicing yarn have passed the cam 741, jacks having butts 737' at the level of the reading point 191 will come around and 65 push the reading point 191 radially outward again. This will push the thrust bar 460 radially outward and the tension spring 310 will pull the sinker slackening cam 309 radially outward again. 70 It will be obvious that in this way the jacks selected the needles which were to take the splicing yarn and that then the same selection of jacks operated the sinker slackening cam. In other words, the individual knitting instrumentalities which control the splicing themselves individually control the width of the slackening 75

and not only will every spliced stitched be slackened, but only those stitches will be slackened.

It is possible to use this butt differentiation to control other of the stitch-making means to give the different length of stitch. Thus in Fig. 5 8 is shown an alternative construction in which the butts of the pattern jacks are used to control the positions of the stitch cam 360' and in this way vary the length of stitch. In this construction, as in the previous one, the jacks which are 10 raised to cause their needles to take the reinforcing yarn are not drawn down all the way so that the operating lever 188 will be held radially outward by the jacks of the needles which take the splicing yarn and the stitch cam will be 15 lowered slightly to draw slacker stitches. In Fig. 8 we have shown only those parts which are necessary to illustrate the differences between the constructions of Figs. 1 to 7, and that of Fig. 8. It will be observed that the butts 737, 737' of the 20 pattern jacks come around to the reading point 191 of the operating lever 188 at two levels, as in the case of the mechanism of Figs. 1 to 7, but the butt differentiation is reversed.

The stitch cam 360' is mounted on a slide 511 25 which permits limited vertical movement of the cam. There is a horizontal pin 512 passing through the slide 511, which pin carries the stitch cam itself. The free end of the pin 512 engages in a jaw 513 carried on a shaft 514 rotatable in a bearing 515 on the upper bedplate. This shaft extends radially outward and its outer end carries a bell crank lever 516. The lower arm of that bell crank lever is connected to the upper end of a bent thrust bar 462. This 30 thrust bar 462 need not extend down to the main pattern drum, as far as concerns its function with the stitch cam. This function is merely to serve as part of the linkage transmitting to the stitch cam the selection of the butts on the pattern jacks. For this purpose the bar is connected with a bent lever 517 whose other end is rigidly connected to a collar 518 on a stationary shaft 519 at the lower rear portion of the machine. Unitary with this collar 518 is an upwardly extending arm 520 linked to a rod 521 pivotally connected to the free end of the operating lever 188. These parts are so arranged that when the operating lever is swung radially outward by engagement with the butts 737 on pattern jacks 50 522, the upper end of the vertical arm 520 will be moved outwardly and the end of the bent lever 517 associated with the bent thrust bar 462 will swing upwardly, raising that thrust bar. The raising of this thrust bar will turn a bell 55 crank lever 516 and its associated shaft 514 and jaw 513, which will lower the pin 512 and the stitch cam 360. When the reading point 191 of the operating lever moves in towards the surface of the needle cylinder, the vertical arm 520 60 will swing forward and the bent thrust bar will be lowered, raising the stitch cam to a position where it will make stitches of normal length.

In this figure we have shown a somewhat different means of taking the stitch slackening 65 mechanism out of operation at the end of the reinforced area. This consists of a thrust rod 463 carrying a horizontal arm 522 underlying the operating lever 188. The operating lever 188 is movable vertically on the post 189 and there can 70 be a coiled spring (not shown) inside the collar above the lever to exert downward pressure on the lever. When the thrust rod rises up onto its cam on the main pattern drum, the arm 522 will raise the operating lever above the level of 75

all the butts 131, 131',—not only the butts 131' at the lower level, but also the butts 131 at the upper level. It might be noted that in this construction the operating lever is normally kept 5 in action at a level where it is pressed radially outward by jacks which were not lowered by the drawdown cam 15, and the operating lever swings inward by passing above the jacks which were lowered by that special drawdown cam. This 10 being the reverse of the arrangement in Figs. 1 to 7, when the operating lever is pushed out by a pattern jack butt, the stitch cam is lowered, causing slackening of the stitch. In either case the butt differentiation controls which wales are 15 slackened. Where the phrase "knitting instrumentalities" is used in the claims, it is intended to include needles and jacks.

Many variations not departing from the scope 20 of this invention will occur to those skilled in the art. Thus the invention can be used, if desired, even if there is to be no reinforcing or splicing of stitches.

What we claim is:

1. In a circular knitting machine, a needle 25 cylinder, stitch-making means associated therewith comprising sinkers and knitting instrumentalities having butts thereon, in combination with means adapted to cause division of the butts of individual knitting instrumentalities into 30 groups, and other means controlled by said butt division to slacken stitches in wales corresponding substantially to the butts of one group of instrumentalities.

2. In a circular knitting machine, a needle 35 cylinder, stitch-making means associated therewith comprising needles and jacks in said cylinder, sinkers associated therewith, butts on said jacks and a knitting cam, in combination with means to cause butt division of the jacks into 40 groups, and means controlled by the butt division to give part of the stitch-making means an extra movement whereby the stitches knit on substantially the needles corresponding to one group of jacks are slackened.

3. In a circular knitting machine, a needle cylinder, knitting instrumentalities in said cylinder having operating butts thereon, sinkers associated therewith and means to operate said sinkers and instrumentalities to produce fabric, 50 in combination with means adapted to move selected instrumentalities vertically to give butt differentiation for the making of local splicing, and means controlled by the differentiation in butts adapted to slacken substantially the spliced 55 stitches only.

4. In a circular knitting machine, a needle cylinder, latch needles, sinkers and a knitting cam adapted to cooperate to produce stitches of one length, said needles having jacks thereunder in 60 said cylinder, in combination with means adapted to give butt differentiation vertically to the jacks in accordance with a pre-selection of jacks, and other means controlled by the differentiation to slacken stitches locally substantially in accordance therewith.

5. In a circular knitting machine, a needle cylinder, instrumentalities in said cylinder having butts thereon, and sinkers associated with said cylinder, in combination with means controlled by the vertical position of the butts on the knitting instrumentalities to slacken stitches locally by movement of sinkers substantially in correspondence to the presence and absence of butts at a given level.

6. In a circular knitting machine, a needle

cylinder having needles and jacks independently movable therein with butts projecting from the surface of the cylinder adapted to be differentiated into groups as to vertical position, and sinkers associated therewith, in combination with means controlled by differentiation in jack butt position to slacken stitches locally by increased movement radially of sinkers corresponding substantially to one group of jack butts.

7. In a circular knitting machine, a needle cylinder, knitting instrumentalities in said cylinder and operating butts on said instrumentalities, in combination with a splicing finger, means for bringing the splicing finger and knitting instrumentalities into and out of yarn engaging position for the making of local splicing, sinkers associated with the knitting instrumentalities and mechanism controlled by the butts of the knitting instrumentalities adapted to slacken the spliced loops by movement of substantially the 20 sinkers corresponding to the instrumentalities making local splicing.

8. In a circular knitting machine, a needle cylinder, knitting instrumentalities in said cylinder having butts thereon, sinkers associated therewith and means adapted to separate the instrumentalities vertically for the purpose of sectional splicing, whereby butt position differentiation is produced, in combination with means including a reading member controlled by the 30 levels of the butts of said instrumentalities adapted to cause special movement of the sinkers to cause local slackening of substantially the reinforced spliced stitches only.

9. In a circular knitting machine, a needle 35 cylinder, needles and jacks therein, the latter having butts projecting from the surface of the cylinder, sinkers associated with the needles and adapted, in cooperation therewith, to produce fabric containing stitches of one length, in combination with means adapted to separate jacks vertically for the purpose of local splicing and means adapted to read at a certain level the absence of the butts of the jacks thus differentiated and cause special movement of associated sinkers so as to produce a different length of stitch on substantially the needles which take the splicing yarn.

10. In a circular knitting machine, a needle cylinder, stitch-making means associated therewith comprising sinkers and other knitting instrumentalities having butts thereon, in combination with means adapted to cause differentiation of the butts of individual knitting instrumentalities, and independent means controlled by said butt differentiation adapted to cause selected individual instrumentalities in said stitch-making means to slacken stitches knit on instrumentalities corresponding substantially to one of the groups of butts established by said differentiation.

11. In a circular knitting machine, a needle cylinder, knitting instrumentalities some of which are in said cylinder, and operating butts on a plurality of the instrumentalities in said cylinder, in combination with means adapted to cause division into groups of the butts of individual instrumentalities in said cylinder for the purpose of varying the yarn-taking positions of the instrumentalities, and other means controlled by the butt differentiation to vary the movement of other individual instrumentalities selectively substantially according to the butt group division.

12. In a circular knitting machine, a needle cylinder, knitting instrumentalities independent-

- ly movable therein having butts projecting from the surface of the cylinder, sinkers associated therewith and means adapted to divide the instrumentalities into groups with their butts at different levels, in combination with means controlled by the presence or absence of butts at a given level adapted to cause extra movement of substantially the sinkers corresponding to one of the groups to slacken the stitches drawn at those sinkers.
13. In a circular knitting machine, a needle cylinder, knitting instrumentalities slidable therein and having butts thereon, sinkers associated with said knitting instrumentalities and slidale transversely thereof, movable cam means for imparting an abnormal inward movement to certain only of said sinkers, said instrumentalities being arranged for division into vertically differentiated groups, detector means for cooperation with said butts for detecting the division of said instrumentalities into groups and movable in response to the presence or absence of butts to impart the aforesaid abnormal inward movement only to those sinkers corresponding to one 10 of said groups of instrumentalities.
